Specification for Design.

Patented Apr. 13, 1920.

Application filed January 2, 1919. Serial No. 269,361. Term of patent 14 years.

To all whom it may concern:

Be it known that I, HAROLD JARVIS, a subject of the King of Great Britain, and resident of the city of Toronto, county of York, Province of Ontario, in the Dominion of Canada, have invented a new, original, and ornamental Design for a Self-Closing Faucet, of which the following is a specification, reference being had to the accompanying drawing forming part thereof.

Figure 1 is a plan view of my improved design for a self-closing faucet.

Fig. 2 is a front elevational view of my improved design for a self-closing faucet.

Fig. 3 is a perspective view of the improved faucet.

I claim:

The ornamental design for a self-closing faucet as shown.

HAROLD JARVIS.
